UNITED STATES PATENT OFFICE.

MICHAEL HAWIE, OF BRIDGEPORT, CONNECTICUT.

RUSTLESS BUCKLE.

REISSUED

1,426,634.

Specification of Letters Patent. Patented Aug. 22, 1922.

Application filed November 12, 1921. Serial No. 514,633.

To all whom it may concern:

Be it known that MICHAEL HAWIE, a citizen of the United States, and resident of Bridgeport, in the county of Fairfield and State of Connecticut, has invented certain new and useful Improvements in Rustless Buckles, of which the following is a specification.

This invention relates to a buckle, and has more especial reference to that type of buckle known as a "rustless back" buckle.

The object of the invention is to provide a simple and practical buckle of the character mentioned which will be effective in the performance of its intended function without the necessity of employing any stitching in incorporating a web with the buckle, and which will be conveniently constructed with particular reference to economy of webbing.

With the above and other objects in view the invention comprises the construction, arrangement and combination of parts as now to be fully described and as hereinafter to be specifically claimed, it being understood that slight changes in minor details of construction and arrangement of parts within the spirit of the invention may be made so long as within the scope of the claims.

30 In the accompanying drawing forming a part of this specification,

Fig. 1 is a fragmentary view in front elevation of the improved buckle as in use;

Fig. 2 is a sectional view on line 2-2 in Fig. 1;

Fig. 3 is a perspective view of the buckle detached from the web; and

Fig. 4 is a rear elevational view of the buckle.

40 With respect to the drawing and the numerals of reference indicated thereon, it will be seen that the buckle is formed of two parts of sheet metal and comprises a frame-member and a lever-member. 10 denotes the frame-member of the buckle, 11 denotes the top edge of said frame, 12 denotes the bottom edge thereof, and 13 represents two ears extended forward in the same direction from the opposite ends of said frame and arranged 45 at approximate right-angles thereto.

50 The lever member consists of an operating arm 14 and a clamping arm 15 having a series of teeth 16 and arranged at an approximate right-angle to the operating arm, 55 and is provided with pintles 17, said pintles extending from the opposite ends of the lever

member and situated at the junction between said operating and clamping arms. Numeral 18 represents perforations in the ears of the buckle frame for receiving the pintles 17.

Adjacent its bottom edge 12 the buckle frame is provided with a series of spaced apart teeth 19, preferably arranged along the full length of said frame and struck from said body to extend upwardly and forwardly therefrom, that is, to be situated upon the same side of the body as are the ears 13, the teeth desirably being of approximate V-shape as stamped from the aligned 70 V-shaped openings 19' in the back.

As will be most clear from the drawing, the pivotal points for the lever member are arranged above the teeth 19 and the teeth 16 of the clamping arm are given a circular movement with each operation of the lever. In this respect it will also be seen that the teeth of the clamping arm are arranged alternately with respect to the teeth of the back so that in the operation of the 80 buckle, see Fig. 3, the teeth of the clamping arm pass between the teeth of the back to insure a free movement of the lever.

Numeral 20 represents a web having an upper reach 21 and a lower reach 22.

85 In assembling the web with the buckle, an end 23 of the web is passed downwardly in front of the frame and in the rear of the lever member, said lever at the time being positioned as in Fig. 3, and inserted between 90 the teeth 19 and the front face of the frame. The teeth are then wedged back toward the openings 19' in the frame to securely grip said end 23. This form of attaching by means of the spaced 95 apart teeth engaging alternate portions of the end of the web and clamping the same in the openings of the back serves to leave exposed portions of the web between the teeth and which lay in alignment 100 with the teeth of the lever member so as to form a yieldable back against which the adjustable portion of the web is clamped. The web is then extended upwardly and over to engage the upper edge 11 of the frame as at 105 24, and is extended downwardly across the rear face of the frame, as at 25 and below said face, to produce the lower reach or loop 22 for holding the usual cast-off 26. That portion of the web which is to comprise the 110 upper reach 21 thereof is then passed upwardly in front of the frame-member and in

rear of the lever-member, the lever-member being still arranged about as it is shown in Fig. 3, in open position. After the upper reach 21 has been adjusted in an obvious 5 manner to the desired position, the operating arm is grasped and moved to the position of Fig. 1, so that the serrated edge of the clamping arm of the lever-member is in engagement with a part of said upper reach 10 21 to press said part firmly against a portion of the web closely adjacent end 23 thereof, and to in turn press said portion firmly against the front face of the frame-member. That is to say, the lever-member is manipulated to firmly secure a double thickness 15 of the web between the serrated edge of the clamping arm of the lever and the upper portion of the frame of the buckle.

The arrangement as fully described, evidently, provides a durable and efficient construction. The teeth of the clamping arm of the lever member are preferably arranged out of alignment with the teeth of the frame member so as to operate in front of the exposed portion of the webbing between the teeth of said frame-member to provide a more flexible and binding engagement with the running portion of the webbing when threaded therebeneath. The teeth 19 can be 20 pushed back to the approximate plane of the frame, with the end of the web very securely fastened between the teeth and the frame, and the buckle lever clamping arm is ideally 25 constructed to positively fasten the upper reach of the web in stationary position. The operating arm of the lever is arranged and constructed to engage the front face of that portion of the web comprising one of the laps of the loop when the clamping arm is in 30 its proper clamping position.

Having thus fully described the invention, what I desire to claim and secure by Letters Patent is:

1. A rustless buckle comprising a sheet 45 metal frame-member and a lever-member, said frame member including a back having forwardly projected ears and a series of spaced apart teeth struck up from said back intermediate its top and bottom edges and 50 extending upwardly and forwardly, the lever-member being pivoted in the ears of the frame and including an operating arm and a clamping arm arranged at an angle thereto and having a series of teeth arranged alternately with respect to the teeth of the frame 55 and adapted in the operation of the lever to pass between and clear of the teeth of the said frame-member.

2. A rustless buckle comprising a frame- 60 member and a lever-member, said frame-member being formed of sheet metal, and having forwardly extended ears, and a series of integral upwardly disposed teeth formed from its body portion, said lever- 65 member being pivotally supported in the

ears of the frame-member and including an operating arm, and a clamping arm arranged at an angle thereto, in combination with a piece of web one end of which is engaged by the teeth of said frame-member 70 and extended upwardly from said teeth and exposed between said teeth and across the front of said frame, thence over its upper edge and down covering the back of the frame, and continued to form a loop and 75 finally extending upward under the clamping arm and in front of the before mentioned attached end portion of the web, so as to be adjustably secured against the web by the said clamping arm, the clamping arm 80 of the lever-member being provided with a series of teeth that operate in alignment with the exposed portion of the web between the teeth of said frame-member to better from a yieldable back against which the adjustable portion of the web is clamped. 85

3. A buckle consisting of a frame having forwardly extending ears, and a lever having an operating arm and a clamping arm, the frame having teeth struck therefrom arranged above the lower edge of the frame and extending upwardly and forwardly, and the lever being pivoted in the ears of the frame, said upwardly and forwardly extending teeth of the frame serving to secure one 90 end portion of a web, the web extending upwardly from the teeth across the front face of the frame and between the ears thereof, thence over the upper edge of the frame, thence downwardly across and against the 95 rear face of the frame and continuing to provide a loop, and finally extending upwardly across and in direct contact with the frame, teeth and before mentioned end portion of the web, and between the frame and 100 lever to be engaged by the clamping arm of the lever and securely clamped against the first mentioned end portion of the web.

4. A buckle consisting of a frame having forwardly extending ears, and a lever having an operating arm and a clamping arm provided with teeth, the lever being pivoted in said ears, and the frame having upwardly and forwardly extending teeth struck therefrom and arranged in spaced relation to the lower edge of the frame, said upwardly and forwardly extending teeth serving to fasten one end portion of a web to the frame, the web extending upwardly across the front face of the frame, and over 110 the upper edge thereof, thence downwardly across and in engagement with the rear face of the frame to provide a loop, thence upwardly between the lever and frame to have direct engagement with the portion of 115 the frame below the upwardly and forwardly extending teeth, with the teeth themselves, and with a considerable area of the first mentioned end portion of the web 120 above the teeth and engaging the front face 125

of the frame, to be better engaged by the teeth of the clamping arm of the lever and securely fastened against the first mentioned end portion of the web, whereby both sets of teeth constitute means for holding the first mentioned end portion of the web and said teeth of the clamping arm of the lever constitute means for insuring the position of the running end portion of the web;

both reaches of the loop being parallel for 10 the full length of the loop, and the body of the frame lying in a plane between the reaches of the loop and parallel with each reach.

Signed at Bridgeport, in the county of 15
Fairfield and State of Connecticut, this 9th
day of November, A. D. 1921.

MICHAEL HAWIE.
